CLASP

Leland P. Knowlton, Worcester, Mass.

Application March 24, 1950, Serial No. 151,575

1 Claim. (Cl. 24—248)

1 This invention relates to new and improved clasps or the like devices.

The principal object of the present invention resides in the provision of a new and improved toothed clasp which is particularly adapted for securely and positively holding relatively lightweight or sleazy materials, e. g., such as are found in catamenial bandages, although the present clasp has many other uses.

A further object of the invention resides in the provision of a clasp as above stated comprising a pair of members each of which has an enlarged end and a small end, said members being pivoted together at the small ends thereof, the larger end of one member having a slot for receiving a tape or the like and the two members at their wider ends being provided with interfitting snap latching means comprising a resilient tab or the like and a hole into which the tab may snap, the teeth on said members being arranged at narrowed waist portions thereof and lying along corresponding edges and being so formed that when the two members are latched together, said teeth interfit but do not touch, and form therebetween a sinuous passage having sharp angles, to the end that said passage will receive and the teeth securely hold loosely woven fabrics as well as other types of fabrics, said teeth securely holding the same and preventing withdrawal thereof.

Other objects and advantages of the invention will appear hereinafter.

Reference is to be had to the accompanying drawings in which

Fig. 1 is a view in front elevation of the novel 35 clasp showing the same closed;

Fig. 2 is a similar figure showing the clasp open;

Fig. 3 is a perspective view showing the clasp partly open; and

Fig. 4 is an edge view looking in the direction of the arrow 4 of Fig. 2.

Much difficulty has been experienced in holding fabrics of loosely woven materials in certain relations where it is necessary to hold such fabrics positively, without bunching, and in such a manner that they are secure and will not give way. Such a relation is to be found in the securement of catamenial bandages and the present invention provides a clasp that will hold them positively without any bunching or give and in a particularly effective manner.

The present clasp comprises a pair of members 10 and 12, each of which has an enlarged end and a small end, the small ends being co-

extensive and rounded, as is clearly seen at 14, to provide for an interpivoting rivet or the like 16. The opposite end of member 10 is enlarged in a substantially flat head 18 which has a cross slot 20 in which a tape or the like may be secured and this slot is provided with a recess 22 in one side edge thereof for a purpose to be described.

Between the enlarged head 18 and the pivot 10 end of member 10, the same is greatly reduced forming a waist portion 24, the same being toothed with large, sharp triangular teeth 26. These teeth are arranged on a line which is substantially midway between the center of the rivet 16 and the center of slot 20 so that tension applied between these points will be exerted along a line at right angles to the line of the teeth 26.

The other member 12 is provided with an enlarged head 28 of substantially triangular form. On this head at an extreme corner thereof, there is a down-turned tab 30 and at the other corner of the head there is another down-turned tab 32 which is adapted to act as a thumb piece, tab 25 30 snapping into recess 22 as shown in Fig. 1 to close the clasp.

Member 12 also has a reduced waist portion indicated at 34 which is provided with teeth 36 substantially complementary to teeth 26 and 30 facing the latter as clearly shown.

When the clasp is to be closed by moving the members from the Fig. 2 position to the Fig. 1 position, it is merely necessary to insert the material to be clasped between the members and then swing them together, because the tab 30 will strike the edge of the head 18 approximately at the point 38 and upon so doing, it very easily distorts member 12 at the head 28 so that tab 30 rides up over the material of the head 18 and then finds and snaps into the recess 22 which is evenly spaced with the tab from the axis of the members in the rivet 16.

The head 28 of member 12 always overlies the side surface of head 18 opposite from the side 45 of member 10 to which member 12 is pivoted, see particularly Fig. 3 wherein it is apparent that member 10 is pivoted behind member 12 but the head 28 overlies head 18 when the members are moved toward each other for closing.

Since the large triangular sharp teeth 26 and 36 do not touch when the clasp is closed, they form between them a sinuous passage having sharp angles; and once a piece of cloth is caught on the teeth, it will be seen that the cloth is 55 positively held by the sharp corners of the teeth.

Any tendency exerted by pulling downwardly on the cloth held, and upwardly on the tab 40, as for instance in the direction of the arrow 42, will not tend to open the clasp because the clasp must be opened with a motion at right angles to the direction of the arrow. In addition, this resistance to accidental opening is greatly enhanced by reason of the fact that member 12 is pivoted at one side of member 10 and latched thereto at the opposite side, thus requiring a definite pressure on tab 32 transversely of the device to release tab 30 from notch 22.

Having thus described my invention and the advantages thereof, I do not wish to be limited to the details herein disclosed otherwise than as set forth in the claim, but what I claim is:

A clasp comprising a pair of flat plate-like members connected at one end by a pivot and having reduced toothed waist portions provided with teeth on their inner edges and enlarged heads on the other ends of said members, one of said members being connected by said pivot to a side surface of the other member and being adapted to yield beyond said pivot such that its head engages the opposite side surface of the head of said other member under tension when the clasp is closed so as to resist unintended opening of the clasp, the head on one of said

members having a recess, and the head on the other member having a tab projecting laterally from the surface engaging said opposite head and receivable in said recess when the clasp is closed, said toothed waist portions on said members being twisted to lie substantially in a common plane and crossing each other and the teeth thereon lying in said common plane and being so arranged that the teeth on one member interfit in the spaces between the teeth on the other member when the clasp is closed, said plate-like members being of relatively thin resilient material and creating a tension on each other when closed with the tab received in the recess.
